CHILD'S SLIPPER

Leo Leslie, Waynesville, N. C., assignor to Welco
Shoe Corporation, Waynesville, N. C.

Application April 25, 1951, Serial No. 14,954

Term of patent 3½ years

(Cl. D7—7)

To all whom it may concern:

Be it known, that Leo Leslie, citizen of the United States of America, residing at Waynesville, in the county of Haywood and State of North Carolina, has invented a new, original, and ornamental Design for a Child's Slipper, of which the following is a specification, reference being had to the accompanying drawing, forming part thereof.

The figure is a perspective view of a child's slipper, showing my new design, the opposite side presenting substantially the same appearance as the side shown.

I claim:

The ornamental design for a child's slipper, substantially as shown and described.

LEO LESLIE.
